CLAIM

The ornamental design for a pooper scooper glove, as shown and described.

DESCRIPTION

FIG. 1 is a perspective view of the outer cover of my design for a pooper scooper glove showing my new design;

FIG. 2 is a front elevational view thereof;

FIG. 3 is a back elevational view thereof;

FIG. 4 is a right side elevational view thereof;

FIG. 5 is a left side elevational view thereof;

FIG. 6 is a bottom plan view thereof;

FIG. 7 is a top plan view thereof; and

FIGS. 8-14 show separately for ease of illustration the insert of the outer cover thereof;

FIG. 8 is a perspective view of the insert of the outer cover thereof;

FIG. 9 is a front elevational view thereof;

FIG. 10 is a back elevational view thereof;

FIG. 11 is a right side elevational view thereof;

FIG. 12 is a left side elevational view thereof;

FIG. 13 is a top plan view thereof; and,

FIG. 14 is a bottom plan view thereof.

The broken lines on the glove represent perforated tear off tabs and is included for the purpose of illustration and does not form part of the claimed design.
